UNITED STATES PATENT OFFICE.

CHARLES MARTIN KOSMINSKI, OF MARYLEBONE, LONDON, ENGLAND.

BEATING APPARATUS FOR CARPETS, FURS, AND THE LIKE.

1,075,042.

Specification of Letters Patent.

Patented Oct. 7, 1913.

Application filed July 13, 1912. Serial No. 703,794.

To all whom it may concern:

Be it known that I, CHARLES MARTIN KOSMINSKI, a subject of the King of Great Britain, residing at 50 Berners street, Oxford street, Marylebone, in the county of London, England, have invented certain new and useful Improvements in Beating Apparatus for Carpets, Furs, and the like, of which the following is a specification.

10 This invention relates to beating apparatus for use in removing dust from such materials as furs, dress materials, clothes or carpets, of the kind in which flexible beating strips are mounted on a rotating drum or 15 carrier.

According to my invention I mount on the rotating drum leather or other beating strips, which are flexible in all directions after the manner of a lash and quite separate from each other so that each gives an independent stroke, the drum being provided with radial vanes over which the strips lap, the ends of the strips being secured at or toward the inner edge of the vanes. This 25 arrangement of vanes and strips gives the desired lashing stroke, the strips striking the material along a substantial part of their face and not at their end, and instantly the blow is given being drawn sharply but 30 lightly along the surface by the pulling action of the vanes. By mounting the beater directly upon the drum of an electric motor I avoid the use of any gearing and simplify the construction and method of operation.

35 As applied to indoor carpet beating I propose to inclose a portable beater in a suitable casing closed except at the bottom and adapted to move over the surface of the carpet, and to connect the casing through a 40 tubular operating handle to a suction apparatus which removes the dust as it is raised by the beaters.

In order that the said invention may be clearly understood and readily carried into effect I will describe the same more fully with reference to the accompanying drawings in which:—

Figure 1 is a front elevation of a beating apparatus embodying my invention and suitable for beating furs, dress materials and the like. Fig. 2 is an end elevation and Fig. 3 a plan of the same, and Fig. 4 shows a carpet cleaning apparatus in which suction is employed to remove the dust raised by the beater, one side of the inclosing casing being removed to show the interior.

A is the electric motor, of a known especially light type in which the external field rotates.

B, B are the beating strips, preferably of 60 leather.

C, C are the vanes mounted on the periphery of the motor and carrying the strips B, which are secured at the inner edges of the vanes and lap over them during rotation of 65 the motor, in the manner shown especially in Figs. 2 and 4.

Referring to the apparatus shown in Figs. 1, 2 and 3, the motor A is mounted on a shaft a carried by the standards d on the base D. 70 The leading wires to the motor pass through the standards d and shaft a so that they are completely concealed and cannot get in the way of any moving parts. The terminal block d' on the base receives the end of the 75 connecting wires d'', which may be provided with a plug at the other end to connect with the source of current supply through a wall or lamp socket or in any other convenient manner. On the base is also carried a rheostat box d³ with regulating switch d⁴ by which the current to the motor may be turned on or off and the speed regulated according to the nature of the work. On the base D may be placed a loose cushion D' 80 over which the work is laid for beating purposes. As the beater revolves the work on the cushion is moved so as to bring all portions under the action of the beating strips. The vanes or wings C are preferably made 85 in the form of light frames, to reduce the weight and air resistance, and the outer bar is slightly concave to prevent the strips B flying off at the sides and becoming entangled with any other parts. Any convenient 90 number of vanes and of beating strips may be employed. The beating action is of the following nature:—When the drum rotates the long flexible strips fly out by centrifugal 95 force and the vanes exercise comparatively little effect upon them as long as they are free. Immediately, however, a strip strikes the work (which it does along a considerable portion of its length and not at the end) its movement is momentarily checked and the 100 vanes over which it laps instantly catches it at some distance from its point of attachment and draws it sharply forward. The 105 effective length or radius of action of the strip or lash is thus changed, as it bends somewhat sharply at the vane, with the result that although the initial blow may be

100

105

110

a heavy one the strip rises the instant the blow has been given and is then drawn lightly and rapidly over the surface of the work. A beater of this kind is more especially intended for use by furriers, drapers and other shop-keepers or warehousemen storing skins or fabrics which require occasional or regular cleaning.

In the carpet cleaning apparatus shown in Fig. 4 the beating strips are of reduced length so as not to strike the light inclosing casing E, which may conveniently be made semi-circular at its upper part with sides forming with the floor a practically closed box to prevent the dust raised by the beater escaping into the atmosphere. The casing carries the light frame e on which the motor is mounted and the leading wires are carried in any convenient manner by the frame, the lower part of which is provided with the rollers e' permitting the apparatus to be readily moved over the carpet. The casing E carries the tubular handle F an extension f of which follows the outline of the casing nearly to its lower edge, along which the suction nozzle f' lies. The tubular handle F, which may terminate in a handle bar such as is used on cycles, is placed in connection with a suction apparatus G of any suitable type so that the dusty air within the casing is continuously removed as the dust is raised by the beater. The handle may carry a small spring contact or switch indicated at f², by which the current to the motor may be controlled and cut off instantly when not required, as for instance when drawing back the apparatus or moving it over an already cleaned surface to a fresh portion of the carpet. The wires to the motor may conveniently be carried through the tubular handle F or be secured externally on it. They are shown diagrammatically in the drawing. The vanes C' are preferably made plain or with a continuous surface and not in the form of a frame as in the first arrangement, as they serve to prevent the dust settling again upon the carpet by disturbing the air inside the casing. It will be seen that the suction nozzle does not act directly on the carpet

as in the well known vacuum cleaning apparatus, but merely carries off the dust already raised as in the existing stationary carpet beating machines provided with suction apparatus. The vacuum need therefore only be a weak one and there is no danger of the fibers of the carpet being removed by the suction.

The carpet beater may be used independently of any suction device but the suction effects the continuous removal of the dust and prevents it escaping into the atmosphere or settling again upon the carpet.

What I claim and desire to secure by Letters Patent of the United States is:—

1. Beating apparatus comprising a rotat-
ing drum, a plurality of sets of independent
flexible beating strips on the said drum,
and radially projecting vanes on the drum,
over which the said flexible beating strips
lap during rotation, which vanes are made
with their outer edges of concave form to
prevent the flexible strips flying off at the
sides of the beater.

2. A beating apparatus comprising a ro-
tatable drum, flexible beating strips and
radial vanes on the said drum, which vanes
have concave edges over which the beating
strips lap, an inclosing casing open at the
bottom and means for applying suction to
the interior of the casing to remove the dust
raised by the beating strips.

3. A beating apparatus comprising a ro-
tatable drum, flexible beating strips and
radial vanes on the said drum, which vanes
have concave edges over which the beating
strips lap, an inclosing casing open at the
bottom, a tubular operating handle for the
casing, a suction nozzle opening at the lower
edge of the casing and communicating with
the said tubular handle, and means for ap-
plying suction through the handle for the
removal of dust directly it is raised by the
beater.

In testimony whereof I affix my signature in presence of two witnesses.

CHARLES MARTIN KOSMINSKI.
